No. 838,487.

PATENTED DEC. 11, 1906.

J. WILKINSON.
ELASTIC FLUID TURBINE.
APPLICATION FILED MAR. 27, 1906.

UNITED STATES PATENT OFFICE.

JAMES WILKINSON, OF PROVIDENCE, RHODE ISLAND, ASSIGNOR TO
WILKINSON TURBINE COMPANY, A CORPORATION OF ALABAMA.

ELASTIC-FLUID TURBINE.

No. 838,487.

Specification of Letters Patent.

Patented Dec. 11, 1906.

Application filed March 27, 1906. Serial No. 308,293.

To all whom it may concern:

Be it known that I, JAMES WILKINSON, a citizen of the United States, residing at Providence, in the county of Providence and State 5 of Rhode Island, have invented new and useful Improvements in Elastic-Fluid Turbines, of which the following is a specification.

My invention relates to elastic-fluid turbines of the multistage type having diaphragms which divide the interior into wheel-compartments.

The object of my invention is to construct the turbine in such a manner that while preserving its strength and rigidity it will enable 15 access to be readily had to all parts of the interior for inspection and repair. To this end I form the outer casing and the diaphragm or diaphragms in halves or segments on a horizontal transverse plane, though the dia- 20 phragm may be divided into a greater number of segments, as occasion may require. The casing serves to clamp the diaphragm-sections together, a yielding packing being interposed between the halves of the casing, 25 so that they can be drawn up solid against the diaphragms.

It is a further object of my invention to provide a novel manner of bracing the segmental diaphragm against axial deflection due to 30 pressure strain. This I do by providing an abutment-bush, which I insert in the shaft-opening of the diaphragm, so that the inner ends of the segments contact therewith and are braced between it and the casing. I fur- 35 ther propose to provide the radial abutting side edges of the segments with portions which interlock, thereby giving additional strength to the diaphragm and forming a bet- 40 ter steam-tight joint.

It is also an object of my invention to pro- 45 vide a novel method of mounting guides or director-plates in the nozzle-passages, this being effected by placing the guides in the nozzle-cores and casting the diaphragm around the ends of the plates to secure them in position by a cast joint.

My invention also contemplates the pro- 50 vision of improved director devices which comprise circumferential and transverse guides preferably formed of thin steel plates joined together in the form of a grid and secured in the diaphragm as above described.

My invention further comprises the details

of construction and arrangement of parts hereinafter more particularly described with, 55 reference to the accompanying drawings, in which—

Figure 1 is a sectional view through the casing of a horizontal multistage turbine, the diaphragm being shown in side elevation. 60 Fig. 2 is an end view of Fig. 1, the upper half being shown in vertical section and the casing broken away on each side of a diaphragm. Fig. 3 is a top plan view of the lower half of the diaphragm and sectional casing shown in 65 Fig. 1. Fig. 4 is a detail view of a circular bush. Fig. 5 shows the several parts in position for assembling. Fig. 6 is a sectional view along the line *x* *x*, Fig. 1. Fig. 7 is a view along the line *y* *y*, Fig. 1. 70

Similar reference-numerals refer to similar parts throughout the drawings.

The outer casing of the turbine is divided on a horizontal transverse plane to form the upper half 1, which is provided with the tongues 2, that enter grooves 3 in the lower half 4. Packing may be interposed in this tongue-and-groove joint, both halves being flanged at their abutting edges to provide for the reception of screw-bolts 5, which detachably connect the casing-sections together. The outer casing is internally grooved at 6 to receive the diaphragms, any desired number of which may be used, according to the design or capacity of the turbine, or the dia- 85 phragms may be designed so their outer peripheries abut, in which case the casing need not be grooved. The diaphragms are also made in halves 7 and 8, which are connected by a tongue-and-groove joint, each 90 half having one or more tongues 9, which interlock, forming a tongue-and-groove joint. These tongues preferably continue around the semicircular opening in the center of each half, which together form the 95 central shaft-opening in the diaphragm. An annular bush 10 is held in this central opening by a circular tongue-and-groove joint, the bush being provided with annular grooves 11, in which the tongues 9 in the 100 walls of the diaphragm-opening interlock. This bush forms a solid central abutment for the diaphragm-halves which is of particular advantage when the internal pressure is high or when the difference in pressure on the two 105 sides of the diaphragm is great; but when

this pressure is low this bush or inner ring may be dispensed with. I show a flanged packing-ring 12 disposed in the center opening of the bush.

5 The halves of the diaphragm are arranged to break in the same plane with the sections of the casing. When the lower halves 8 of the diaphragms have been seated in the grooves 6 of section 4 of the casing and the bushes 10, (if such are to be used,) inserted, the upper sections of the diaphragms are disposed so that they interlock properly with their corresponding lower sections. After this yielding packing, such as 13, is interposed in the grooves 3 and the top section 1 of the casing slipped over the diaphragms. As the screws 5 are screwed home the packing 13 yields until the casing-sections are pulled up solid against the diaphragms. 10 Packing may be used in the grooves 6, if desired, or between the diaphragm-sections or around the bushes 10. By removing the screws 5 ready access may be had to the interior of the whole turbine for inspection or 15 repair.

The diaphragm is provided with a peripheral shoulder 14, through which one or more nozzle-passages 15 lead diagonally for the purpose of discharging motor fluid at an 20 angle against a bucket-wheel. (Not shown.) As these nozzles are radially and circumferentially elongated for the purpose of increasing their capacity in proportion with the expanded condition of the steam, it becomes 25 necessary to provide both circumferential and transverse guides or director-plates to prevent eddy-currents. According to my invention I provide a wrought-sheet-steel or a cast-steel grid comprising transverse guides 30 16 and circumferential partitions 17, which give the best nozzle effect in directing the steam. I may use any desired number of the guides 16 or partitions 17 in each nozzle, either joining them together or forming them 35 as an integral body. When the nozzle is short circumferentially, only the transverse guides 16 need be used. I prefer to cast the diaphragm around these guides 16 or the grid, so as to make the whole diaphragm 40 practically an integral piece. To this end I pack the guides in the cores for their respective nozzle-passages, the ends of the guides and partitions being sufficiently wider 45 or longer than the nozzle-cores to project therefrom. The nozzle-cores are then placed in the diaphragm-mold and the diaphragm cast around the ends of the guides or partitions, their ends being provided with 50 perforations 18 to root them more securely 55 in the metal. This cast joint for both guides and partitions secures them firmly in position at a minimum cost, avoiding all machining or cutting of the diaphragm, which is not weakened by their insertion. 60 The sections of the diaphragm may be locked 65

together by a single tongue and groove, if desired, the tongue being formed integrally or attached to the diaphragm-section. To an extent the purpose of this feature of my invention may be obtained by providing the 70 sections with overlapping shoulders.

Having thus described my invention, what I claim as new, and desire to secure by Letters Patent, is—

1. In an elastic-fluid turbine, a diaphragm 75 formed in sections which have a tongue-and-groove joint at their abutting edges, and a central abutment-ring locked between said sections.

2. In an elastic-fluid turbine, a diaphragm 80 formed in sections which are connected by a radial tongue-and-groove joint or joints, and a central tongue-and-grooved abutment-ring.

3. In an elastic-fluid turbine, a diaphragm 85 divided in halves, the abutting portions of said halves being provided with tongues and grooves which interlock to form a tongue-and-groove joint between the halves, and a central circular abutment carrying a packing-ring. 90

4. In an elastic-fluid turbine, a sectional outer casing with a yielding packing-joint, a sectional diaphragm which fits between the halves of said casing, and means to draw the casing-sections together until they clamp the 95 diaphragm-sections together.

5. In an elastic-fluid turbine, sectional diaphragms, a sectional casing to clamp over said diaphragms, a yielding packing between sections of the casing, and means to draw 100 said casing-sections together against said packing.

6. In an elastic-fluid turbine, a sectional diaphragm, and a solid abutment-bush disposed centrally of the diaphragm and locked 105 in position between its sections.

7. In an elastic-fluid turbine, a sectional diaphragm provided with a central shaft-opening, one or more tongues and grooves formed in the walls of said opening, and a 110 solid bush held between said sections by a tongue-and-groove joint.

8. In an elastic-fluid turbine, a stationary element, a nozzle-passage formed therein, and radial and circumferential partitions or 115 guides connected together and having their ends rooted in the end and side walls of said nozzle-passage.

9. In an elastic-fluid turbine, a diaphragm 120 having a nozzle-passage formed therein, and a grid comprising transversely and circumferentially disposed members which are united together and cast-jointed to said diaphragm so as to divide or partition said nozzle-passage, substantially as described. 125

10. In an elastic-fluid turbine, a stationary element, a nozzle-passage leading therethrough, thin metallic guide-plates of greater width than said nozzle which are held in position therein by having their ends united by 130

a cast-joint to said element, and locking perforations provided in the ends of said plates which are rooted in said element.

11. In an elastic-fluid turbine, a diaphragm formed in sections which have a tongue-and-groove joint at their abutting edges, and an outer sectional casing which surrounds and holds said sections together to form a steam-tight partition in the turbine.

12. In an elastic-fluid turbine, a diaphragm formed in sections, the abutting edges of the sections being adapted to make a steam-tight joint, each being provided with one or more members adapted to interlock lengthwise of the joint, and an outer sectional casing which surrounds and holds said sections together to form a steam-tight partition in the turbine.

13. In an elastic-fluid turbine, a segmental diaphragm exposed to different fluid pressures, a casing inclosing said diaphragm, and an abutment disposed centrally of the diaphragm and contacting with the inner edges

of the segments thereof to prevent the deflection of the diaphragm from pressure strain.

14. In an elastic-fluid turbine, a shaft, a segmental diaphragm exposed to different fluid-pressures and provided with a central shaft-opening, a casing inclosing said diaphragm, an abutment-bush disposed in the shaft-opening of the diaphragm and in contact with the inner edges of the segments, said bush being adapted to brace the diaphragm - sections against deflection from pressure strain, and a packing-ring for said shaft carried by said bush.

In testimony whereof I have hereunto set my hand in presence of two subscribing witnesses.
